(57) **CLAIM**

The ornamental design for a table, as shown and described.

DESCRIPTION

FIG. 1 is a first front perspective view of one embodiment of a table showing our new design.

FIG. 2 is a front elevation view of the embodiment of the table of FIG. 1.

FIG. 3 is a left side elevation view of the embodiment of the table of FIG. 1.

FIG. 4 is a right side elevation view of the embodiment of the table of FIG. 1.

FIG. 5 is a top plan view of the embodiment of the table of FIG. 1, with the left side elevation view being a mirror image of the same.

FIG. 6 is a bottom plan view of the embodiment of the table of FIG. 1; and,

FIG. 7 is a first front perspective view of two pair of adjacent tables of FIG. 1.

Broken lines are for the purpose of illustrating environment and form no part of the invention.

1 Claim, 6 Drawing Sheets(56)
